UNITED STATES PATENT OFFICE

2,532,436

JOURNAL BOX LID

Nicholas H. Arnold, Chicago, Ill., assignor to
 Standard Railway Equipment Manufacturing
 Company, Chicago, Ill., a corporation of Dela-
 ware

Application September 7, 1946, Serial No. 695,406

5 Claims. (Cl. 308—47)

1

This invention relates to journal boxes for railway cars and more particularly to an improved spring for biasing the lids of such boxes toward closed position.

The principal object of the invention is to provide such a pre-tensioned spring adapted to exert its pressure against substantially the center of the lid, and wherein the ends of said spring are arranged so as to pass substantially around the periphery of the lid and bear thereagainst when the lid is in closed position to cause said lid to tightly engage the edges of the journal box opening.

Another object of the invention is the provision of an improved spring for journal box lids for holding said lids in open or closed position in respect to an associated box, said spring being formed with coils concentric with the axis of hinge means for the lid, and other coils adapted to bear against the central portion of said lid to bias said lid toward closed position.

Another object of the invention is to provide a spring for a journal box lid, which spring is provided with pre-tensioned spaced coils which cooperate with each other to bias the lid toward closed position, and wherein said spring tension is insufficient to overcome resistance thereto when said lid is in open position.

Other objects and advantages will appear in the following description thereof.

In the drawings:

Figure 1 is a plan view of a journal box lid hinged to a journal box and having the invention applied thereto.

Figure 2 is a half top plan view of Figure 1.

Figure 3 is a section on line 3—3 of Figure 1.

Figure 4 is a section similar to Figure 3 showing the lid in partly open position.

Figure 5 is also a section similar to Figure 3 showing the lid in fully opened position.

Figure 6 is a side elevation of one-half of the spring showing, in dotted lines, the spring as it appears when the coils are tensioned and as they would appear applied to the lid as in Figure 3.

In the drawings the journal box is shown at 1, formed with a hinge lug 2, provided with an aperture for pivotally connecting an associated lid 3 therewith, and with angularly disposed surfaces 4 and 5 for engagement by the spring biased upper central extension 6 of said lid 3.

The lid 3 is formed preferably of pressed sheet steel and is provided with a pair of hinge eyes or hooks 7 integrally formed on its upper edge, one at each side of the lug, and the lid is hingedly connected to the journal box by a pin 8 which

2

extends through said eyes 7 and the aperture of the lug 2 and is held in place by cotter 9. Otherwise the lid is of the usual form, with the exception of a pair of laterally spaced panels 10 formed in the body portion thereof.

The resilient means for holding or biasing the lid toward closed position is shown at 11 and comprises a tension spring, which is bent in substantially channel form, as at 12, intermediate its ends so as to extend behind the lug 2, passing under the pin 8. Each arm of said portion 12 is formed into a coil 13 which surrounds the pin 8 between lug 2 and eyes 7, as clearly shown in Figures 1 and 2. From the coil 13 each spring 15 wire extends downwardly (11) over the face of the lid to substantially the center thereof and is formed into a coil 14, each located within a panel 10. From the coils 14 each spring wire is formed so as to extend about the periphery of a panel 10, as shown in Figure 1. It will be noted that the outer margins of the panels are located approximately over the edges 15 of the journal box opening and consequently the spring bears not only against the center of the lid but against substantially the periphery thereof as well, resulting in a tight contact of the lid against said edges 15.

In Figure 3 it will be noted that when the lid is in normal position bearing flatly against the edges 15 of the box opening, the inner surface 30 of the extension 6 of the lid bears against the surface 4 of the lug. When it becomes desirable to raise the lid, extension 6 is forced to slide up over the cam surface 16 between surfaces 4 and 5, against the tension of the spring (see Fig. 4) 35 until said extension 6 passes said cam surface 16 and rests upon surface 5, as seen in Figure 5. The hinge eyes or hooks 7 are sufficiently loose on pin 8 and the extension 6 inherently slightly resilient to allow extension 6 to move between surfaces 4 and 5 of lug 2. In this position the tension of the spring is insufficient to cause the lid to pass downwardly over cam surface 16 to normal closed position.

Figure 6 shows, in full lines, one-half of a 40 spring unassembled and with no tension in the coils. In dotted lines the spring is shown tensioned and as it would appear applied to a lid in closed position, as in Fig. 3. In other words, arm 12 is moved anti-clockwise to the position shown in dotted lines, which will pre-tension coils 45 13, in which position the spring is applied to the journal box, pin 8 passing through said coils 13. The arms 17 also must be brought to the position shown in dotted lines which will pre-tension coils 50 14. Thus it is apparent that when the spring is 55

applied to the box and lid, coils 13 and 14, both of which are pre-tensioned, cooperate to bias the lid toward closed position, and that since the ends of the spring extend substantially around the periphery of the lid, said lid is finally held against the edges of the journal box opening.

The spring is held to the lid in the usual manner, as by the clamps 18, riveted to the lid and passing over the arms of the spring below coils 14.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a journal box having a hinge lug projecting upwardly therefrom and provided with angularly disposed surfaces and a hinge pin associated with said lug for pivotally connecting an associated lid therewith; a unitary spring adapted to be mounted upon said lid and formed with a portion engageable with said lug to hold said lid in open or closed position upon said box, said spring having coils formed therein adjacent said portion encircling said pin on opposite sides of said lug, and other coils formed therein spaced from said portion, said lid having an extension bearing against one of said surfaces when in closed position and against the other of said surfaces when in open position, said coils cooperating to bias said lid toward closed position.

2. In a journal box having a hinge lug projecting upwardly therefrom and a hinge pin associated with said lug for pivotally connecting an associated lid therewith; a spring adapted to be mounted upon said lid and formed with a portion extending behind said lug to hold said lid in open or closed position upon said box, said spring having coils formed therein adjacent said portion adapted to encircle said hinge pin on opposite sides of said lug, and other coils formed therein spaced from said portion, said coils cooperating to bias said lid toward closed position.

3. In a journal box having a hinge lug projecting upwardly therefrom and a hinge pin associated with said lug for pivotally connecting an associated lid therewith; a spring adapted to be mounted upon said lid and formed with a portion extending behind and on opposite sides of said lug to hold said lid in open or closed position upon said box, said spring having spaced aligned coils formed therein encircling said hinge pin

when applied to said box, and other coils formed therein adapted to bear against the central portion of said lid, said coils cooperating to bias said lid toward closed position.

4. In a journal box having a hinge lug projecting upwardly therefrom, and provided with angularly disposed surfaces having a cam surface therebetween and a hinge pin associated with said lug for pivotally connecting an associated lid therewith, a spring adapted to be associated with said lid and formed with a portion extending substantially around said lug, said spring having longitudinally spaced coils formed therein adjacent said portion adapted to surround said pin on opposite sides of said lug, and other coils formed therein spaced from said portion adapted to bear against the central portion of said lid, said lid having an extension bearing against one of said surfaces when in closed position and passing over said cam surface to the other of said surfaces when in open position, said coils cooperating to bias said lid toward closed position, said cam surface holding said lid open against the bias of said coils.
5. In a journal box having a hinge lug projecting upwardly therefrom and a hinge pin associated with said lug for pivotally connecting an associated lid therewith; a spring adapted to be mounted upon said lid and formed with a portion engageable with said lug to hold said lid in open or closed position upon said box, said spring having coils formed therein eccentric with the axis of said hinge pin when applied to said box, and other coils formed therein adapted to bear against the central portion of said lid, said coils cooperating to bias said lid toward closed position, the ends of said last mentioned coils provided with extensions engageable with the periphery of said lid.

NICHOLAS H. ARNOLD.
